DUST GUARD

Albert Vigne, Webster Groves, and Isaac Eugene Cox, Kirkwood, Mo., assignors to National Bearing Metals Corporation, St. Louis, Mo., a corporation of New York

Application February 5, 1938, Serial No. 188,839

3. Claims. (Cl. 286—6)

Our invention relates to a dust guard and particularly to that type of dust guards which are used in connection with the journal boxes of railway cars. Such guards are positioned in a slot or channel formed in the rear wall of the journal box and surrounding the part of the axle projecting through said rear wall.

One object of our invention is to provide a dust guard for journal boxes which will not only prevent entrance of dust and other foreign matter from the exterior of the box but which will form an effective seal against the escape of oil from the box either around the axle or along the walls of the channel in which the guard is positioned.

Another object of our invention is to provide a guard which will be simple in construction so that it may not only be manufactured at low cost but may be readily placed in position without the use of special tools.

A further object of our invention is to provide a dust guard which will be sufficiently rigid and durable to withstand the strains and stresses to which it is subjected by the relative movement of the axle and box and will retain its resiliency for a long period of time.

In the accompanying drawing which illustrates one form of dust guard made in accordance with our invention Figure 1 is a vertical central section through the rear end of a railway journal box to which our guard is applied; Figure 2 is a front elevation of the guard alone; and Figure 3 is an enlarged section taken on the line 3—3 of Figure 2.

Referring first to Figure 1, the numeral 5 indicates a railway journal box in the rear wall of which is formed a slot or channel 6 to receive the dust guard. This wall also has formed in it an opening 7 for the passage of the axle 8 carrying wheel 9. The portion of the axle passing through the wall is provided with an enlarged shoulder or "dust guard fit" 10 with which the guard makes contact as hereinafter described.

The dust guard consists essentially of three parts, a rear or seal plate 11, a front or retainer plate 12, and an interposed sheet 13. This sheet 13 may be composed of any porous material having the necessary characteristics of resiliency, elastic compressibility, and flexibility. We prefer, however, to employ cellulose sponge specially treated as described in our co-pending application Serial No. 124,374 of February 6, 1937. Our preference for the use of this material is based upon the fact that it not only complies with the requirements above set forth but it is particularly effective as a lubricating medium. The seal

plate 11 and retainer plate 8 are preferably both made of the shape shown in Figure 2 having straight tops and rounded bottoms, their size being somewhat less than the contour of the channel 6 to permit the necessary movement of the axle relative to the box. Both plates are preferably made of hard fibre board or similar material. The opening in plate 11 is of such size as to form a snug running fit with the collar or "guard fit" 10 of the axle. This prevents movement of the guard relative to the axle in either a vertical or lateral direction. The opening 14 in plate 12 is larger than that in plate 11 and the inner edge of this opening is rounded or beveled as shown.

Plates 11 and 12 are connected at their tops and bottoms by tie members 15 and 16, respectively. These tie members are formed of cotton webbing or other flexible but preferably non-elastic material. Their width is such as to permit the sheet 13 to expand to its normal thickness as shown in Figure 3. When in this expanded condition, the distance between the rear face of plate 11 and the front face of plate 12 should be considerably greater than the distance between the walls of channel 6 so that the guard must be compressed before insertion into the channel and the plates are held firmly against the walls of the channel by the compressible elasticity of the sheet. One edge of tie member 15 is connected to the inner face of plate 11 by staples 17 or similar fastening means, which means also attaches sheet 13 to said plate. In like manner one edge of tie member 16 is connected to plate 11 by staples 18 which also pass through sheet 13. In addition to these fastening devices, we prefer to employ a series of staples 19 arranged in annular formation around the opening in plate 11 and securing sheet 13 to said plate. It will be understood that all of these fastening means 17, 18 and 19, whether staples or other devices, should be let into the outer face of plate 11 so as not to interfere with its contact with the wall of the channel and that their length should be such that they will not strike against plate 12 when the guard is in its compressed condition. The opposite edges of tie members 15 and 16 are secured to the outer face of plate 12 by staples 20 and 21, respectively.

To prevent these edges from interfering with the contact of the outer face of this plate with the wall of the channel, they are positioned in rabbets 22 and 23 in said face.

To seal the open top of the slot or channel 6 against the entrance of water, dirt or other for-

esign matter, we employ a sealing strip 24 of the same material as sheet 13. This sealing strip is both longer and wider than the length and width of the channel so that when the guard is installed in the channel, the sealing strip must be compressed to enter the channel and so bears firmly against the walls thereof both at the sides and ends. The sealing strip is preferably secured to the guard by means of staples 25 passing down vertically through said strip and the web of tie member 15.

In placing our guard in position, plates 11 and 12 are forced toward each other, compressing sheet 13, until the thickness of the guard is sufficiently reduced to permit its insertion in channel 6. After the lower part of the guard has entered the channel, pressure on the plates is released, permitting the elasticity of sheet 13 to force the plates firmly against the walls of the channel. The guard is now forced completely into the channel, as shown in Figure 1, the sealing strip 24 effectively closing the open upper end thereof. The axle opening 26 in sheet 13 is considerably smaller than collar 10 of the axle so that when the axle is inserted through it, the inner edge of the sheet will be bent over to form a sealing lip 13', as shown in Figure 1. This lip is confined between the collar 10 and the rounded edge of opening 14 in plate 12. The size of opening 14 should be greater than the diameter of the part 10 of the axle by an amount equal to twice the flexed thickness of lip 13'. This amount should, however, be appreciably less than twice the normal or uncompressed thickness of sheet 13 so that the edge of opening 14 will effect a certain amount of compression on lip 13' to insure effective contact of the lip with the axle under all conditions.

Having fully described our invention, what we claim as new and desire to secure by Letters Patent of the United States is:

1. In a dust guard, a seal plate, a retainer plate, a sheet of porous elastic material positioned between said plates and exerting lateral pressure thereon, upper and lower tie members of non-elastic pliable material connecting said plates but permitting movement thereof toward and away from each other, and a sealing strip of porous elastic material carried by the upper tie member. 5

2. In a dust guard, a seal plate, a retainer plate, said plates having straight tops and rounded bottoms, a sheet of porous elastic material positioned between said plates, means securing said plates together but permitting movement thereof toward and away from each other, said means including a tie member of non-elastic pliable material located at the straight top edges of the plates, and a sealing strip of porous elastic material carried by said tie member. 10 15

3. In a dust guard, a seal plate of rigid material having an opening forming a running fit with an axle, a retainer plate also of rigid material and having an opening for the reception of an axle, each of said plates having flat outer faces, a packing sheet of porous elastic material interposed between said plates and having an inner 25 lip projecting through the opening in the retainer plate for contact with an axle, the diameter of the opening in the retainer plate being greater than the axle diameter by substantially twice the normal thickness of the lip, said packing sheet 30 being secured to the seal plate but not directly connected to the retainer plate, the elasticity of the packing sheet functioning to force the flat outer faces of said plates directly against the wall of a dust guard channel, and a non-elastic pliable 35 tie member connecting said plates to retain them in proper relative position during installment.
